UNITED STATES PATENT OFFICE.

AUGUST BUERMANN, OF NEWARK, NEW JERSEY.

DESIGN FOR A PATTERN FOR CASTING BRIDLE-BITS.

SPECIFICATION forming part of Design No. 13,652, dated February 27, 1883.

Application filed December 6, 1882. Term of patent 14 years.

To all whom it may concern:

Be it known that I, AUGUST BUERMANN, of Newark, in the county of Essex and State of New Jersey, have invented a new and useful Improvement in Designs for Patterns for Casting Bridle-Bits, of which the following is a specification.

My invention relates to the design of a pattern for casting the mouth-piece for bridle-bits from malleable iron or other metal; and it consists in the features substantially as herein-after set forth.

The figure is a plan which shows the points embraced in my invention.

The features of my invention, as shown, are the mouth-piece A, made tapering from both ends into the port-section B. The port is a loop extending out from the mouth-piece, at right angle with it, having the parallel sides

C; or the sides may be flaring, approaching nearer together toward the point or end D. The ports may be of different lengths, according to need, and be within the intent of my invention. Across the port is the bar E, and at the mouth of the port is the closing-section F, making a connection in line with the ports of the mouth-piece A, and this section across the mouth of the port is an especial feature of my invention.

I claim—

The design for a bridle-bit pattern, having the taper sections A, port B, bar E, and section F, substantially as specified and shown.

AUGUST BUERMANN.
